P.A.—The Patent Professor ®(57) **CLAIM**

I claim the ornamental design for a medical bandage, as shown and described.

DESCRIPTION

FIG. 1 is a top front isometric view of a medical bandage showing my new design;

FIG. 2 is a top rear isometric view thereof;

FIG. 3 is a top front isometric view of an alternate configuration thereof;

FIG. 4 is a top front isometric view of a different alternate configuration thereof;

FIG. 5 is a front elevation view thereof;

FIG. 6 is a rear elevation view thereof;

FIG. 7 is a left side elevation view thereof;

FIG. 8 is a right-side elevation view thereof;

FIG. 9 is a top plan view thereof; and,

FIG. 10 is a bottom plan view thereof.

The broken lines in the drawings show portions of the medical bandage that form no part of the claimed design.
